UNITED STATES PATENT OFFICE.

RALPH JOSEPH, OF LONDON, ENGLAND.

FOLDING STOOL AND THE LIKE.

Application filed May 12, 1924. Serial No. 712,804.

To all whom it may concern:

Be it known that I, RALPH JOSEPH, a subject of the King of Great Britain, of 41 Heathdene Road, Streatham, London, England, have invented a new and useful Improvement Relating to Folding Stools and the like, of which the following is a specification.

This invention has for its object to provide an improved form of folding stool adapted for combination with or embodiment in other articles.

According to the principal embodiment of this invention the top or seat of a stool is adapted to fold up and form a bag and the lining thereof, whilst the leg portion of the stool is constructed to fold up and be enclosed within the outer covering of the bag which is divided along suitable lines and adapted to be fastened and unfastened for this purpose; for example, the top of the stool may be constructed in the manner of a hinged frame such as constitutes the mouth of a lady's hand bag, and to this frame is attached the combined seat top and bag lining, the outer covering of the bag, and the folding stool legs which when erected may be of the X leg or other suitable type.

In modified arrangements the folding frame may be combined with bags of various types such as attaché cases, and so forth.

The accompanying drawings show one construction of combined folding stool and lady's hand bag carried out in accordance with this invention.

Fig. 1 is a front elevation, and Fig. 2 is an end elevation of the folding stool as erected for use.

Fig. 3 is a front view showing the stool folded within the compass of the bag, a portion of the material of the bag being removed to show the parts more clearly.

Fig. 4 is an end view of Fig. 3 with the material of the bag in section.

In the construction shown in the drawings the seat frame *a* of the stool is circular and consists of two semi-circular members hinged together so as to fold on the diameter of the seat, which thus takes the form of the usual folding frame of a lady's hand bag and is fitted with a clip fastening *b* as usually provided therefor.

The seat frame *a* is provided with a circular deflatable air cushion *c* adapted to be inflated by blowing into a valve *c'* which can be readily operated for deflation. This de-

flatable air cushion *c* folds in half with the seat frame as in Fig. 3 so as to form the lining of the hand bag.

The edges of the deflatable seat cushion *c* are clamped between the frame *a* and rim plates in the manner usual with bags, and the external bag covering *d* is also attached to the folding seat frame *a* in any suitable manner.

The folding under frame of the stool is attached to the combined folding seat and bag frame *a* and consists of two U-shaped members *e* pivoted to the bag or seat frame *a* at a suitable distance inside the hinges thereof whilst the bends of the U frame *e* are hinged together as at *e'* and provided with hinged loop-like extensions so that the frame when erected is of X formation.

To secure a more compact article when folded the lower loop-like frames of the X frame structure are made in two section frames *f'* *f''* hinged together at *f''*, the cross bars of the lower section *f''* being connected together in the centre by a hinge pin *f''*. The lower end of each section *f''* are bent so as to form stops *g* which overhang the bars of the lower section *f''* and thus provide a stop or abutment therefor when the sections are unfolded and extended for use as shown in Figs. 1 and 2.

The sections *f'* of the X frame are secured together by horizontal stay bars *h* hinged to one member *f'* and hooked on to an extension of the hinge pin *f''* on the other member *f'*.

If desired the lower portion of the X frame may be made in one piece.

The outer covering *d* of the bag is attached to the edge of the combined folding seat and bag frame *a* and is made in two portions fastened together by suitable tabs *d'* and press buttons *d''* or other suitable means.

It will be seen that the combined article when folded up as in Figs. 3 and 4 may be carried and used as a lady's hand bag which can be opened and closed and used in the usual manner. The deflated seat cushion *c* forms the lining of the bag for holding articles in the usual way and an additional pocket such as *i* is provided on the outside as shown in Figs. 2 and 4. When the use of a stool or seat is required the outer covering *d* of the bag is unfastened, the mouth of the bag is opened out, the folding X leg stool frame attached to the folding bag and seat

frame *a* is unfolded and erected, the combined bag lining and seat *a* is inflated all as shown in Figs. 1 and 2 and a comfortable stool is provided ready for use.

5 As soon as required the stool frame is folded up again, the seat cushion *c* is deflated, the mouth of the bag formed by the folding frame is closed, and the outer covering *d* fastened together, all as shown in Figs. 3 and 4, when the article is again ready for use as a hand bag.

10 The combined bag frame and folding stool structure may be made of aluminium, steel, wood, compressed paper, or other suitable material, and the metal frames are plated or rendered rust proof in suitable manner. If desired the frames may be suitably perforated for lightness sake as indicated at *j* in Fig. 2 or in other suitable 15 manner.

15 The shape and general fashioning of the bag may be altered as required, and the combined folding seat and bag frame instead of being circular as shown, may be 20 square, oval, polygonal, or otherwise designed as may be required by the selected shape of the bag.

25 The folding stool frame may be modified so as to be of any suitable folding construction, and suitably divided into extending or folding sections to bring the same effectively within the compass of the bag.

30 Press buttons or other suitable fastenings may be employed for securing the overlapping parts of the outer bag covering.

35 If desired, the folding stool frame may be combined with an attaché case or the like so arranged that the whole or a portion of the

latter will form the seat portion of the stool in combination with the upper end of the 40 erected stool frame.

What I claim as my invention and desire to secure by Letters Patent is:—

1. A combined folding stool and hand bag 45 wherein the folding frame which forms the mouth of the bag is adapted when opened out horizontally to form the seat frame of the stool whilst the folding stool legs are attached to said frame and are adapted to be folded up and covered by the outer covering 50 of the bag.

2. A combined folding stool and hand bag comprising a folding stool frame, the seat portion of which folds in half to form the folding frame of a hand bag, a combined bag lining and seat cushion consisting of a deflatable air cushion attached to the seat portion of the folding stool frame, a bag covering which encloses the leg portion of the stool when folded up, and means for releasably fastening the bag covering in position. 55

3. A combined folding stool and hand bag comprising a folding stool frame the seat portion of which consists of rim plates 60 hinged diametrically to fold in half and form the folding frame of the hand bag, a combined bag lining and seat cushion consisting of a deflatable air cushion, means for clamping the edges of the deflatable air 65 cushion to the folding rim plates of the seat portion of the stool, a bag covering which encloses the leg portion of the stool when folded up, and means for releasably fastening the bag covering in position. 70

RALPH JOSEPH.
